CLAIM

The ornamental design for a gear with gearing casing as shown and described.

DESCRIPTION

Figure 1.1 is a first side view of a gear with gearing casing showing the new design;

Figure 1.2 is a second side view thereof;

Figure 1.3 is a front view thereof;

Figure 1.4 is a rear view thereof;

Figure 1.5 is a third side view thereof;

Figure 1.6 is a fourth side view thereof;

Figure 1.7 is a first front perspective view thereof; and

Figure 1.8 is a second front perspective view thereof.

The following design shows a gear casing containing a gear. The broken lines depict portions of the gear with gearing casing that form no part of the claim.
